UNITED STATES PATENT OFFICE.

WILLIAM H. PATTERSON, OF BALTIMORE, MARYLAND.

ELEVATOR.

SPECIFICATION forming part of Letters Patent No. 257,182, dated May 2, 1882.

Application filed August 15, 1881. (No model.)

To all whom it may concern:

Be it known that I, WILLIAM H. PATTERSON, a citizen of the United States of America, residing at Baltimore city, in the State of Maryland, have invented certain new and useful Improvements in Elevators; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

I provide a vertically-sliding gate or guard operated directly by the movement of the elevator-platform, whereby to insure the closing of the approach to the hatchway in the absence of the elevator therefrom. I provide improved means for closing the safety-gate by the raising or lowering of the elevator, whereby the gate is opened and held open when the elevator is in receiving position and closed when the elevator is not in such position in the hatchway. This automatic operation of the sliding gate is important in avoiding the necessity for personal attention or the possibility of neglect to close it, and because the closing of the gate is thereby rendered certain at the time required.

Referring to the accompanying drawings, Figure 1 represents the floor-entrance to the hatchway of an elevator and the appliances below the floor for operating the gate or guard, which is shown as closed; Fig. 2, a vertical section of the same, showing the elevator in position within the hatchway and the gate open; Fig. 3, a similar section, showing the elevator below the hatchway and the gate closed; Fig. 4, a similar section, showing the elevator above the hatchway and the gate closed; Fig. 5, the platform-racks, and Fig. 6 a detail view of the rack and toothed wheel engaged.

In the drawings, *a* represents the floors of the building; and *b*, the hatchways, in which the elevator is adapted to operate in the usual manner. The platform *c* of the elevator moves in the usual guide-structure, and may be of the ordinary construction. A gate or guard, *d*, is fitted to slide vertically between the grooved supports or posts *e e*, placed at the hatchway-entrance of each floor.

The gate may be made of wire, a light wooden frame or a bar being only intended as a guard against accidents from an exposed hatchway. It is hung by cords *f f*, passing over pulleys *g g* in the grooved posts, and which cords, passing down through the floor and through direction-apertures, which may be provided with friction-pulleys, if desired, are connected with winding and unwinding drums *h h*, fixed upon a shaft, *i*, fitted in hangers *j j*, below the floor, so that the turning of the drums *h h* winds the cords and raises the gate when the platform is in proper position or flush with the hatchway, and unwinding allows the gate to drop or close by its gravity when the platform leaves the hatchway exposed by its moving upward or downward. The means for effecting this I will now describe.

The shaft of the winding and unwinding pulleys is arranged parallel with the gate, and carries two toothed wheels, *kk*, and two ratchet-wheels, *l l*, the former being fitted to turn loosely and the latter fixed upon said shaft and provided with pawls *m*, pivoted to the toothed wheels and held engaged with the ratchet-wheels by springs, so as to form a clutch, whereby the toothed wheels are locked upon the shaft, so that each turns with it in one direction, but free of the shaft when the latter turns in the opposite direction. These wheels must therefore be placed side by side, and I prefer also to arrange them by the side of the winding-pulleys, as shown. Vertical racks *n n* are secured to the same edge of the platform at or near the opposite corners, one extending above and the other below said platform and in position to engage with the toothed wheels as the platform passes through the hatchway. Each of these racks engages with and operates one of the toothed wheels, winding-shaft, and pulleys, and thus opens the gate as the elevator approaches the hatchway, and keeps the gate open as long as the elevator remains in a receiving position within the hatchway. The movement of the elevator from its position in the hatchway releases the rack from the toothed wheel, causing the gate to drop or close by its weight, the other rack and toothed wheel offering no resistance to this closing of the gate, from the fact, as before stated, that the toothed wheels work loosely on the shaft in opposite di-

rections. It will be understood that one of these racks operates to open the gate in the upward movement of the elevator and the other in the downward movement of the elevator, and that the closing of the gate takes place at the moment the acting rack is released. The non-acting rack, though engaged at the same time with its toothed wheel, does not prevent this release by reason of said toothed wheel slipping on its shaft, and the gate having sufficient weight to turn back the winding-wheels to unwind the cords.

The extent of the opening of the gate is regulated by the length of the rack and the relative diameters of the toothed wheels and winding-pulleys. The form of the teeth shown is such as to give flat acting faces only on one side and a beveled non-acting face.

In an elevator passing through several stories the hatchway on each floor is provided with the sliding gate and the winding device beneath the floor, so that the elevator-platform racks will engage with such winding devices in passing from one story to another, leaving the gates of all the hatchways closed except the one at which the elevator is being used.

I have shown and described a single vertical sliding gate; but it is obvious that the other side of the elevator may be provided with a gate operated in the same manner and at the same time.

I claim—

1. The combination, with an elevator-platform provided with vertical racks and a vertically-sliding hatchway gate or guard carried by winding-cords, of a winding and releasing device arranged below the hatchway and operated by the elevator-racks, whereby to wind the cords in opening the gate, and to release the winding device to allow the gate to automatically close, substantially as described, for the purpose specified.

2. The elevator-racks carried by and projecting vertically above and below the elevator-platform, in combination with toothed wheels adapted to engage with said racks, winding and unwinding drums, and a clutch device for each toothed wheel, and a vertically-sliding gate for the hatchway, connected by winding and unwinding cords, substantially as described, for the purpose specified.

3. In an elevator the combination of a sliding guard-gate, an elevator-platform, and the vertical racks thereof, with winding means for raising and lowering said gate, the said winding means consisting of a toothed wheel and clutch on the winding shaft, as set forth.

In testimony whereof I have affixed my signature in the presence of two witnesses.

WILLIAM H. PATTERSON.
